UNITED STATES PATENT OFFICE.

ZENON P. LEGER, OF MONCTON, NEW BRUNSWICK, CANADA.

AUTOMATIC AIR-BRAKE APPARATUS FOR RAILWAY TRAINS AND THE LIKE.

Application filed May 1, 1922. Serial No. 557,775.

To all whom it may concern:

Be it known that I, ZENON P. LEGER, a subject of the King of Great Britain, residing at Moncton, Province of New Brunswick, Canada, have invented certain new and useful Improvements in Automatic Air-Brake Apparatus for Railway Trains and the like; and I do hereby declare that the following is a full, clear, and exact description of the invention, such as will enable others skilled in the art to which it appertains to make and use the same.

The present invention relates to new and useful improvements in an automatic air brake apparatus for railway trains and the like.

The primary object of the invention is the provision of an automatic air brake apparatus so constructed that the air brakes on a railway train or the like will be instantaneously applied upon the derailment of the train.

Another object of the invention is the provision of an automatic electrically actuated mechanism for applying the air brakes on a railway train or the like upon the derailment of the said train, or the derailment of one or more of the cars thereof.

Still another object of the invention is the provision of automatic means for returning the brakes to their inoperative position after they have originally been applied upon the derailment of the train.

A further object of the invention is the provision of an apparatus which is held in inoperative position by its connection with an electric circuit which will be broken upon derailment causing the actuation of the apparatus and the applying of the brakes together with means for returning the mechanism to its initial position after the said brakes have been thus applied.

A still further object of the invention is the provision of an apparatus such as above referred to, which will be comparatively simple and inexpensive to manufacture, reliable and efficient in use, and readily operated.

With the above and other objects in view, the present invention resides in the novel features of construction, formations, combinations, and arrangements of parts, to be hereinafter more particularly described, claimed

and illustrated in the accompanying drawings forming a part of the present application, and in which:

Figure 1 is a side elevation of the invention with the controlling valve in open position;

Figure 2 is a similar view looking from the opposite side of the device;

Figure 3 is a top plan view thereof;

Figure 4 is a longitudinal sectional view taken through the device showing the valve in closed position;

Figure 5 is a view similar to Figure 4 with parts broken away showing the forward switch in open position;

Figure 6 is a detail view showing the means for actuating the forward switch;

Figure 7 is a diagrammatic view illustrating the wiring of the apparatus;

Figure 8 is a similar view illustrating the means for cooling the electro-magnet;

Figure 9 is a sectional view showing the contact post upon one of the journal boxes; and,

Figure 10 is a vertical transverse sectional view taken on the line 10—10 of Figure 4.

Referring now to the accompanying drawings by corresponding characters of reference throughout the several views, the numeral 11 denotes in general a base upon which my improved apparatus 12 is mounted. This base is positioned at any location within one or more of the cars of a railway train (not shown in the drawings) and is connected by a pipe 13 to the air brake system which is likewise not shown.

The pipe 13 leads to one end of a cylinder 14 mounted in suitable brackets 15 upon the base 11. An outlet pipe 16 extends from the cylinder 14 and forms a means through which the air is exhausted from the air brake system when the valve 17 which slides within the cylinder 14 is in open position.

The valve 17 is formed with the sliding member 18 which is mounted in a guide 19 secured in brackets 20 to the base 11.

The forward end of the member 18 is provided with an upturned lip 21 (Fig. 5), while slidable within the support 18 is a plate 22 which is provided with an upstanding arm 23 which is pivoted at its upper end as at 24 to one end of a link 25, the opposite end of which is eccentrically journalled as at

26 to a gear 27 which is mounted on a shaft 28 supported in a standard 29 secured to the base.

A shaft 30 is journalled parallel to the shaft 28 and carries a pinion 31 keyed thereto. This pinion 31 meshes with the before described gear 27 and is operatively connected to the motor 32 by a train of gearing shown at 33. See Figure 3.

10 Obviously upon the operation of the motor 32 the valve 17 will be drawn from open to closed position through the instrumentality of the before mentioned gearing.

Forward and rear switches are shown in Figure 7 at 34 and 35 and comprise stationary disks 36 and 37, the former of which is provided with contact members 38 and 39, and the latter with similar contact members 40 and 41.

20 Switch arms 42 and 43 are journalled in the disks 36 and 37 upon shafts 44 and 45 and are adapted to engage the contact members 38 and 39 or 40 and 41 in a manner to be hereinafter referred to. The contact members 23 38 and 40 are connected by a conductor 46, while the members 39 and 41 are connected by a conductor 47.

A conductor 48 leads from the shaft 44 and switch arm 42 to the motor 32, while a conductor 49 leads from the motor 32 to an electro-magnet 50. A conductor 51 leads from the shaft 45 and switch arm 43 to a suitable part of the truck frame 52 which may be a journal box and which is normally 35 in contact with one of the rails of the railway track 53 through the medium of a car wheel.

Another of the wheels 54 is provided with the usual journal box 55 insulated from the truck frame 52, and is equipped with a contact post 56 to which a conductor 57 is attached which is in circuit with the motor 32 and likewise with the electro-magnet 50 by its connection with the conductor 49.

45 The conductor 57 is connected respectively to the positive and negative terminals of a battery 58, while a conductor 59 leads from the electro-magnet 50 to the before described conductor 51.

50 A suitable indicating lamp is shown at 60 and is connected by the conductors 61 to the conductor 57 upon opposite sides of the battery 58 so as to supply current thereto when the switch 62 is in closed position, as will be 55 hereinafter described.

The rotatable element 63 of the switch 34 which makes contact between the contact plates 38 and 39 by virtue of its connection with the shaft 44 is of circular formation 60 and is provided with peripheral ratchet teeth 64 which are designed for engagement with the yoke 65 carried at one end of an operating rod 66 which is pivoted as at 67 to the before described link 25 and obviously 65 upon rotation of the gear 27 the switch arm

42 will be moved from open to closed position.

The electro-magnet 50 is mounted on a suitable bracket 68 and has journalled adjacent thereto a rocker shaft 69 provided with a forwardly extending arm 70 which carries the contact bar 71 of the electro-magnet.

A pair of rearwardly extending arms 72 project from the opposite end of the shaft 75 69 and have links 73 and 74 connected thereto.

As shown in Figure 4, the link 74 is pivotally at its lower end to a latch member 75 which engages an extension 76 formed upon 80 the lower side of the support 18 for locking the valve 17 in closed position.

Each of the links 73 and 74 carries a switch element 77 which serves to open and close the circuit including the conductors 61 85 and signal lamp 60. The switch elements 77 compose the switch 62 above referred to.

Springs 78 serve to hold the rocker shaft 69 in the desired position and to assist in the proper movement thereof.

The movable element 79 of the switch 35 which is connected to the shaft 45 is provided with a plurality of peripheral gear teeth 80 which mesh with the rack 81 pivotally supported in a bracket 82 carried by the member 18 and serves upon the movement of the member 18 to move the switch arm 43 into engagement with either of the contact plates 40 or 41 as desired.

A spring 83 is attached at its opposite 100 ends to the cylinder 14 and member 18 respectively and serves to assist in their proper movement by drawing the valve 17 to its closed position.

The rocker shaft 69 is provided with an upwardly directed arm 84 provided with a terminal eye 85 through which an operating rod 86 passes.

The rod 86 is pivotally connected as at 87 at one end thereof to the link 25, while the opposite end is provided with a stop 88 for a purpose to be later explained.

As clearly shown in Figure 6 of the drawings the movable element 79 is connected to the shaft 45 by a pawl and ratchet mechanism 89 so that the shaft 45 will be rotated upon movement of the rack 81 in but one direction only.

As shown in Figure 8 of the drawings the electro-magnet 50 is surrounded by a suitable coil of pipe 90 through which cooling fluid may be directed for the purpose of preventing said magnet from overheating.

The operation of the device is as follows:

The valve 17 is normally in closed position, while the switch arm 42 is in contact with the contact plate 39 and the switch arm 43 in contact with the plate 40.

When in this position the circuit including the motor 32 is in open position and the

bar 71 is in contact with the cores of the electro-magnet 50 being held in such position by the closed circuit of the magnet which includes the conductors 57 and 59 and 5 the engagement of the wheel 54 with the rail 53 and likewise the conductor 51 and the truck 52.

In case of derailment, as the wheel 54 leaves the rail 53, the magnet circuit will be 10 broken de-energizing the magnet 50 and releasing the bar 71. The springs 78 will immediately rock the shaft 69 releasing the trip 75 from the member 76 and the spring 83 will draw the valve to its open position 15 thus releasing the air within the air brake system and instantly applying the brakes.

The movement of the valve to open position obviously causes the actuation of the rack 81 which by its engagement with the 20 gear teeth 80 moves the switch arm 43 into contact with the plate 41. This movement obviously closes the motor circuit and sets the motor into operation which, through the instrumentality of the train of gearing 25 33, the pinion 31 and gear 27, draws the valve 17 forwardly to closed position, thus again releasing the brakes and permitting the train to again proceed on its course after the wheels 54 have been replaced upon the 30 track.

When the valve 17 moves to open position upon the derailment of the train, the switch 62 will be moved to closed position which obviously closes the circuit including the 35 signal lamp 60 indicating that the valve in the air brake system has been opened.

Upon return of the several parts to their 40 initial positions by the operation of the motor, the switch 62 will be opened and the lamp 60 extinguished.

Upon the return of the valve to its closed 45 position, the yoke 65 carried by the rod 66 will throw the switch arm 42 from the contact member 39 into engagement with the contact member 38, obviously breaking the motor circuit and causing the said motor to cease operation.

From the foregoing description taken in 50 connection with the accompanying drawings, it will be manifest that an automatic operated mechanism for air brake systems

used in railway trains and the like is provided, which will fulfil all the necessary requirements of such a device, and it should be understood in this connection, that various minor changes in the specific details of construction can be resorted to within the scope of the appended claims, without departing from the spirit or sacrificing any of the advantages of the invention. 60

Having thus fully described the invention, what I claim as new and desire to protect by Letters Patent is:—

1. The combination in an apparatus of the character described, of a valve, magnetic 65 means for retaining the valve in closed position including a circuit closed when the train to which the apparatus is applied is run on the track, said circuit being opened upon derailment of said train to release the valve, 70 means for forcing the valve to open position upon its release, and means including a motor for returning the valve to closed position after derailment.

2. The combination in an apparatus of 75 the character described including a valve for controlling the air brake system of a train, magnetic means for locking the valve in closed position, said means being operable to release the valve upon the derailment of the 80 train, means for forcing the valve to open position upon its release, means including a motor for returning the valve to its closed position, and switches for controlling the 85 operation of the motor upon the release of the valve to set the motor in operation and upon the return of the valve to closed position to stop the motor.

3. In an apparatus of the character described, the combination of a valve for controlling the air brake system of a railway train or the like, means for moving the valve to open position and applying the brakes upon the derailment of the train, a motor for subsequently returning the valve 95 to closed position, and means for automatically starting and stopping the operating motor when the valve is in open and closed positions respectively.

In witness whereof I have hereunto set 100 my hand.

ZENON P. LEGER.
